G. GAYDOS

STEAM GENERATOR

Filed May 6, 1925

Inventor:

George Gaydos,
By Bruce Townsend & Brickerstein,
Attorneys.

UNITED STATES PATENT OFFICE.

GEORGE GAYDOS, OF BROOKLYN, NEW YORK.

STEAM GENERATOR.

Application filed May 6, 1925. Serial No. 28,457.

This invention relates to steam generators of relatively small size and particularly to generators adapted to supply steam to cloth steaming apparatus such as used in tailor

5 shops.

Objects of the invention are to simplify the construction of generators of the type stated and to provide an efficient and reliable generator of small size and relatively 10 large capacity. More specifically, an object is to provide a compact generator having a steam boiler surrounded by an annular water reservoir in which the water is pre-heated.

15 Apparatus embodying the invention is illustrated in the accompanying drawings, in which the figure is a vertical central section through the steam generator, certain of the parts however being shown in elevation.

20 In the embodiment illustrated, the numeral 1 indicates the supporting base which is preferably a triangular shaped plate or casting carrying three vertically disposed standards 2 and supporting a gas burner 3. A casing 4 is fixed to the standards 2 and is provided with inwardly extending flanges 5 arranged at or below the level of the burner top, suitable openings 6 being provided at the lower end of the casing to insure an adequate supply of secondary air for the burner. The standards 2 carry brackets 7 upon which rests a spider 8, upon which in turn rests the flange or enlargement 9 of a vertically disposed cylindrical boiler 10. The steam outlet pipe 11 projects above and axially of the boiler and is provided with a finely perforated extension 12 within the boiler, the latter acting as a water separator 25 which prevents particles of water from entering the steam pipe. The boiler 10 is of such diameter that the sides thereof are spaced from the standards 2 and a water coil 13 surrounds the lower part of the boiler, communicating therewith at the lower end thereof and at a point intermediate the same.

30 As the boiler is intended for use in connection with cloth steaming operations or for other purposes in which there is an intermittent demand for large quantities of steam, the boiler 10 holds a comparatively small quantity of water and it is necessary to provide a water reservoir for periodically replenishing the water in the boiler. The water reservoir comprises an annular tank

having a bottom wall 14 which rests upon the outwardly turned flange 15 provided by the top edge of the casing 4. The outer wall 16 of the reservoir terminates well below the lower end of the water trap 12 of the 60 steam pipe, but the inner wall 17 of the reservoir which lies against the standards 2 is extended upwardly to the top of the boiler 10 and serves as a casing for the upper portion of the steam generator. Water may 65 be supplied from the reservoir to the boiler through a pipe 18 which extends from the bottom of the reservoir to the lower end of the water coil 13 when the fuel supply pipe 19 is closed. As the water reservoir is under 70 atmospheric pressure, this simultaneous control of the water and fuel supply is essential as the pressure within the boiler while the steam is being generated would prevent the inflow of water and might force the boiler 75 water and steam into the reservoir. The simultaneous control is advantageously secured by providing a valve casing 20 having spaced passages under the control of a single valve cock 21, the passages comprising portions of the water feed line 18 and the gas feed line 19, respectively. The valve cock and casing are so arranged that one passage, for instance the water passage, will close before the other or gas passage opens. The 80 gas line is provided with a main valve 19', and a pilot flame is of course provided by a pipe 22 which may tap the gas line 19 between the valve casing and the gas supply, or which may be fed through the casing 85 by a small by-pass. The water supply pipe 18 is preferably provided with a drain cock 23.

85 A tripod 24 joins the upper ends of the standards 2 to hold them in fixed position and carries a sleeve 25 through which the steam pipe 11 passes. The standards 2 extend above the outer ends of the tripod 24 and support a conical cover 26, the cover being held in place by a cowl 27 and nut 28 which is threaded upon the sleeve 25. The cover 26 terminates in a depending flange 27' which drops below the upper end of the casing 17, the cover and flange being spaced 100 from the casing to permit the escape of products of combustion.

105 The casing 4, inner wall 17 and the cover 26 may be provided with linings 29 of asbestos or other heat insulating material.

110 As illustrated, steam is supplied through

pipe 11 to a cloth steamer 30, but the generator may be used in connection with other apparatus.

The steam generator is placed in operation by turning the valve cock 21 to supply fuel to the burner. Ordinarily the water in the boiler is already heated and a rapid generation of steam results, the steam passing out of the pipe 11, free from water, to the cloth steamer. When the steaming operation is completed, the cock 21 is turned to extinguish the flame, and when desired the rotation of the cock is continued to open the water line 18. The reservoir water preheated by conduction through the wall of the casing 17, flows into the boiler through the lower end of the water coil 13. As the steam pressure will fall rapidly when the heat is cut off, water flows into the boiler but cannot flood the same since the top of the reservoir is below the level of the top of the boiler. The annular shape of the reservoir permits the holding in reserve of a large quantity of preheated water, without, however, any risk of introducing too much water into the boiler. The arrangement of the water feed line 18 and the single controlling valve permits a very simple arrangement and construction of the generator, resulting in a compact, enclosed structure.

It will be apparent that the invention is not limited to the embodiment herein illustrated and described, since, for example, the supporting framework and the specific construction of the valve may be varied considerably without departing from the spirit of the invention. These and many other changes in the parts, their relative size, shape and location, are to be understood as falling within the scope of the following claims.

I claim:

1. A steam generator comprising a boiler and a fuel burner beneath the same, means supporting said boiler and burner, a water reservoir open to atmospheric pressure, and

a water pipe connecting said boiler and reservoir, a valve in said connecting pipe, said reservoir circumscribing said boiler and spaced therefrom to provide a passage for the products of combustion, whereby the water supply in said reservoir is preheated before reaching said boiler. 50

2. A steam generator as claimed in claim 1, wherein said boiler is provided at the top thereof with a steam outlet pipe, the entrance to which is positioned above the level of the top of said reservoir. 55

3. A steam generator comprising a supporting frame, a vertically disposed cylindrical boiler carried thereby, a burner beneath said boiler, a water coil surrounding said boiler and communicating therewith at the lower end thereof and at a point above the lower end, a water reservoir under atmospheric pressure, a water pipe connecting said reservoir and the lower end of said water coil, a fuel supply pipe for said burner, and valve means closing said water pipe when said fuel pipe is open, said valve means comprising a valve casing having spaced passages through which the water supply and the fuel supply, respectively, must pass, and a valve in said casing operative to close 75 one of said passages before the other is opened. 60

4. A steam generator comprising vertically disposed standards, a boiler within and spaced from said standards, a water coil 80 at the lower end of said boiler, a fuel burner beneath said boiler and coil, an annular water reservoir carried by and outside of said standards, the inner wall of said reservoir extending above the same and above said 85 boiler, a flanged cover supported from said standards and spaced from the top of said inner wall to provide an outlet for the products of combustion, and a steam pipe extending upwardly from said boiler and 90 passing through said cover.

In testimony whereof, I affix my signature.

GEORGE GAYDOS.
